(57) **CLAIM**

The ornamental design for a hydrofoil mast as shown and described.

DESCRIPTION

FIG. 1 is a front, left perspective view of a hydrofoil mast according to my new design;

FIG. 2 is a front view thereof;

FIG. 3 is a rear view thereof;

FIG. 4 is a top view thereof;

FIG. 5 is a bottom view thereof;

FIG. 6 is a left side view thereof; and

FIG. 7 is a right side view thereof; and,

FIG. 8 is a rear, right perspective view thereof.

The broken lines illustrate portions of the hydrofoil mast that form no part of the claimed design.
